(57) **CLAIM**

We claim the ornamental design for a control knob for cooking appliances with animated icon, as shown and described.

DESCRIPTION

FIG. 1 is a front elevation view of a control knob for cooking appliances with animated icon, showing a first image in a sequence thereof;

FIG. 2 is a front elevation view of the control knob for cooking appliances with animated icon, showing a second image in a sequence thereof;

FIG. 3 is a front elevation view of the control knob for cooking appliances with animated icon, showing a third image in a sequence thereof;

FIG. 4 is a front elevation view of the control knob for cooking appliances with animated icon, showing a fourth image in a sequence thereof; and,

FIG. 5 is a side elevation view of the control knob for cooking appliances with animated icon.

The appearance of the transitional image sequentially transitions between the images shown in FIGS. 1-4. The process or period in which one image transitions to another image forms no part of the claimed design.

The broken line immediately adjacent the shaded edge surface in FIG. 5 illustrates the boundary of the claimed design and forms no part thereof. The remaining broken lines in FIGS. 1-4 illustrate portions of the control knob and portions of the icon which form no part of the claimed design. The outermost solid circular line depicts the control knob and all solid and broken lines therein depict portions of the icon.
